Primary Examiner — Cynthia Ramirez*Assistant Examiner* — Xavier Marti-Santos(74) *Attorney, Agent, or Firm* — Kunzler Bean & Adamson, PC; Michael Bartholomew(57) **CLAIM**

The ornamental design for a bottle for cosmetics, as shown and described.

DESCRIPTION

FIG. 1 is a front and top exploded perspective view of a bottle for cosmetics, showing my new design.

FIG. 2 is a rear and bottom exploded perspective view thereof.

FIG. 3 is a front exploded view thereof.

FIG. 4 is a rear exploded view thereof.

FIG. 5 is a left side exploded view thereof.

FIG. 6 is a right side exploded view thereof.

FIG. 7 is a top plan view thereof.

FIG. 8 is a bottom plan view thereof; and,

FIG. 9 is another perspective view in closed position.

The broken lines shown in the drawings are included for the purpose of illustrating portions of the bottle for cosmetics that form no part of the claimed design.
